The ornamental design for a water exercise floatation device, as shown and described.

DESCRIPTION

FIG. 1 is a front elevation of a water exercise floatation device showing the new design;
FIG. 2 is a top plan view thereof;
FIG. 3 is a left side elevation thereof; the right side view being identical thereto;
FIG. 4 is a bottom plan view thereof;
FIG. 5 is a rear elevation thereof; and,
FIG. 6 is a perspective view thereof.
